UNITED STATES PATENT OFFICE

147,358

DESIGN FOR A TEXTILE FABRIC

Hans W. Wilde, North Bergen, N. J.

Application January 31, 1947, Serial No. 136,562

Term of patent 3½ years

(Cl. D92—1)

To all whom it may concern:

Be it known that I, Hans W. Wilde, a citizen of the United States of America, residing in North Bergen, county of Hudson, and State of New Jersey, have invented a new, original, and ornamental Design for a Textile Fabric, of which the following is a specification, reference being had to the accompanying drawing, forming part thereof, wherein the figure is a plan view of a textile fabric showing my new design. The dot and dash lines on the drawing outline a design unit, which unit is repeated in regular succession as indicated by the extensions beyond the unit boundaries.

I claim:

The ornamental design for a textile fabric, substantially as shown and described.

HANS W. WILDE.
